(57) **CLAIM**

The ornamental design for a cradle for wearable device, as shown and described.

DESCRIPTION

FIG. 1 is a perspective view of a cradle for wearable device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference view thereof showing the state that the wearable device is attached to the subject design.

The broken lines depict portions of the cradle for wearable device that form no part of the claimed design.
